PIANO

Henry R. Heller, New York, N. Y., assignor to
 Winter & Company, New York, N. Y., a corporation of New York

Application September 30, 1936, Serial No. 103,376

3 Claims. (Cl. 84—194)

My invention relates to pianos, and has to do more particularly with an improved tone of piano which will occupy a relatively small floor area.

With the modern tendency toward small living apartments, pianos of heretofore standard size have been found undesirable for the reason that they require unavailable space. Attempts to reduce the size of pianos, however, have generally resulted in instruments of poor tone quality as well as low volume. The matter of volume is not of primary importance but the discriminating piano purchaser demands an instrument of first class tone, even though it be of so-called "apartment" size.

15 An object of my invention is to provide a piano which will occupy a relatively small floor area and will also be comparatively low, as distinguished from the old fashioned "upright" style, and at the same time will have tone quality and volume substantially equal to that of the heretofore standard styles of pianos.

20 A further object is to provide a piano of the type referred to which will be relatively inexpensive to fabricate, simple in construction, and attractive in appearance.

25 Various other objects and advantages will become apparent as the description proceeds.

I have found that if an auxiliary sounding board is provided, as described hereinafter, in 30 addition to the usual sounding board, a relatively small piano will have a tone quality substantially as good as that of a much larger piano of standard design, as well as adequate volume. I have also found that these advantages are enhanced 35 when the sound box or cabinet of a piano is so supported as to hang substantially free of the structure supporting the keyboard portion of the piano. In such design, with a minimum of contact with the floor or other supporting surface, the sound box is permitted to vibrate with a 40 minimum of damping effect.

45 Referring now to the drawing forming a part of this specification and illustrating a preferred embodiment of my invention:

Fig. 1 is a rear elevation of a preferred embodiment of my invention;

Fig. 2 is a fragmentary sectional view taken substantially on line 2—2 of Fig. 1;

Fig. 3 is a side elevation of the piano shown 50 in Fig. 1; and

Fig. 4 is a side elevation showing another style of piano embodying my invention.

The piano cabinet 10, according to my invention, is provided with strings 12, which may be of standard or any other suitable type and carried 55

by a string plate 13. Adjacent the strings 12 is a main sounding board 15, which may be of standard or other suitable design, said board being acoustically connected to the strings 12 by a bridge 16.

5 Spaced outwardly from the main sounding board 15 is an auxiliary sounding board 18, said auxiliary sounding board being preferably secured to diagonal tone bars 20 which normally back up the main sounding board 15. The auxiliary 10 sounding board 18 is attached to the tone bars 20 by suitable means, such as, for instance, screws 21 or the like, and it is preferred that said auxiliary sounding board be acoustically integral with the main sounding board 15, this being accomplished 15 by placing adhesive of any suitable type between the tone bars 20 and the main sounding board 15 on the one side and the auxiliary sounding board 18 on the other.

It will be seen from Fig. 2 that the main and 20 auxiliary sounding boards are spaced from each other so as to define tone chambers 25.

The auxiliary sounding board may take any desired shape, but in my preferred embodiment as shown in Fig. 1, it is formed somewhat smaller 25 in its overall dimensions than the main sounding board, leaving a free margin 26 wherein the main sounding board is not backed up by the auxiliary board. I have found that the best results are obtained when the auxiliary board has an area 30 which is approximately seventy percent that of the main board.

The auxiliary sounding board may be made of acoustical material similar to the main sounding board, such as of seasoned wood.

35 In a preferred embodiment of my invention, the case 10 is suspended substantially free of the floor, and is provided with laterally extending end portions 30 which extend rearwardly from the keyboard housing 32, said laterally extending portions 30 being supported by legs 35. The piano is further supported under the keyboard housing 32 by legs 36. Said legs 35 and 36 may be connected at the lower portion thereof by means of a bar 38, although this bar may be omitted, if 40 desired. Thus, it will be seen that the major portion of the case or cabinet, constituting the tone chamber, hangs substantially free of contact with the floor and is thus susceptible of a maximum amount of vibration, with a minimum of damping.

45 Fig. 4 illustrates a modified form of the piano shown in Figs. 1—3. In this embodiment the keyboard housing 40 is supported by means of legs 42 and the cabinet, tone chamber or sound box 50

55

- 45 is supported from the floor by means of a restricted number of casters 46, for example, one or two. Said casters may, if desired, be mounted in rubber or other resilient material and, in any event, exert such a slight degree of damping on the tone chamber 45 as to be negligible in this respect, so that said tone chamber functions substantially similarly to that of the embodiment shown in Figs. 3 and 4.
- 5 10 15 20
- 10 It will be apparent that the auxiliary sound board described above may be used in types of pianos other than those shown and described herein, as for example, in those of the so-called "grand" type.
- 15 Various changes coming within the spirit of my invention may suggest themselves to those skilled in the art, and hence I do not wish to be limited to the specific embodiments shown or uses mentioned, except to the extent indicated in the appended claims, which are to be interpreted as broadly as the state of the art will permit.
- 20
- I claim:
1. For use in a piano, a main sounding board, an auxiliary sounding board peripherally spaced inwardly from and substantially parallel to the plane of the main sounding board, and bar means

substantially integrally connected to the main sounding board and on the opposite side thereof to the auxiliary sounding board throughout the length of said bar means between said boards.

2. For use in a piano, a main sounding board, an auxiliary sounding board peripherally spaced inward from and substantially parallel to the plane of the main sounding board, and bars adhesively connected to the main and auxiliary sounding boards throughout the lengths of said bars between said boards, said bars and boards together forming a tone chamber open only at the peripheries of said boards.

3. For use in a piano, a sound box, means supporting said sound box whereby the latter hangs substantially free, a main sounding board mounted in said box, an auxiliary sounding board mounted in said box and substantially parallel to and spaced from said main sounding board, the periphery of said auxiliary sounding board being spaced inwardly from that of said main sounding board, and elongated means between and substantially integrally connected to the sounding boards throughout the contiguous areas of said elongated means and boards.

HENRY R. HELLER.
